Patented Nov. 21, 1922.
2 SHEETS—SHEET 2.

UNITED STATES PATENT OFFICE.

PERCIVAL J. WOOD, OF PATERSON, NEW JERSEY.

METHOD OF FORMING PRINTING SURFACES.

Application filed August 6, 1921. Serial No. 490,225.

To all whom it may concern:

Be it known that I, PERCIVAL J. Wood, a citizen of the United States, residing at Paterson, in the county of Passaic and State 5 of New Jersey, have invented certain new and useful Improvements in Methods of Forming Printing Surfaces, of which the following is a specification.

In certain kinds of printing with rollers 10 or plates it is desired to obtain graded-tone effects; for instance, the printing of fabrics for dress goods and the like is frequently done in clouded or mottled effects, splotches or stripes, usually with set figures (without 15 tone-grading) also brought out. Heretofore it has been the custom to produce graded-tone effects on the surface to be treated by forming the numerous minute recesses or incisions (generally of the stipple 20 kind) one by one by hand, of course properly varying them as to size so as to obtain the graded-tone effect. In the printing of fabrics, as in many other kinds of printing, it is usual to proceed by the etching process; 25 but the present invention broadly contemplates, in the art of printing, the production of recesses or incisions in either a varnish or other mere coating surface or in the surface forming the actual printing surface, the only 30 prerequisite being that the surface to be treated, whichever it is, shall be sufficiently soft to yield to the incising or engraving media. The object of the invention is to eliminate the tedium and loss of time and 35 labor that are incident to the preparation of the printing surface for producing in the printing these graded-tone effects. The result of the invention as shown by actual practice is to cut down the time required to 40 prepare the surface for the printing of the graded-tone effect so that it is a matter of a few minutes instead of hours, as heretofore.

The invention is broadly the method of 45 producing graded incisions in the surface to be treated which consists in forcing into said surface the acting faces of an assembly of 50 gravers while said assembly is maintained in convergent relation to said surface; in the best form of the invention and especially 55 with the object and result of obtaining variegated or diversified effects the gravers are yielding. The maintaining of the assembly of gravers in convergent relation to the surface being treated may be a matter of supporting the same, connected as a unit, at a higher elevation than said surface; or it

may be an incident of the relative forms of the acting face of the gravers-assembly and the surface to be treated so that they do not conform, as by the gravers-assembly presenting a convex face. I shall hereinafter by example describe ways of carrying out my method which fall in both these classes, claiming herein specifically those which fall within the first class and reserving for a 60 separate application such as fall within the second class.

In the drawings,

Figures 1 to 8 illustrate the first class and 70 Figures 9 to 11 the second.

Figure 1 shows in section a stencil or support used in carrying out the invention according to one way;

Figure 2 shows a printed piece with 75 graded effects;

Figure 3 illustrates a form of implement that may be employed;

Figure 4 shows a varnished copper roller 80 with the stencil thereon in position for performing my method;

Figure 5 is a view, mainly in section, showing the said roller, stencil and implement at the moment the implement acts to form incisions in the varnish surface of the roller;

Figure 6 shows mainly in section a varnished copper roller with a device including a stencil or support thereon preparatory to carrying out the invention according to another way.

Figure 7 shows an implement that may be used with the device seen in Fig. 6;

Figure 8 shows in section and on a magnified scale the parts shown in Fig. 6 at the moment of forming the incisions;

Figure 9 shows a tampon that may be used in carrying out my invention according to still another way;

Figure 10 shows in section and on a magnified scale this tampon and the surface to be treated at the moment of forming the incision; and

Figure 11 the effect produced in the surface treated when an implement like that shown in Fig. 9 is employed.

Describing, first, ways for example which fall within the first class:

A stencil or support *a* is provided which is to expose an area of the surface to be treated having some selected form, as the 110 stripe *b* or the outline of a cloud, splotch or some such irregular figure *c*, as in the

printed piece shown in Fig. 2. There is also provided, Fig. 3, an implement whose working portion is composed of a set of yielding gravers arranged like the bristles of a brush; in the illustration this implement is constituted by a piece of card clothing *d* (such as is used in carding wool, etc.) attached to one end of a preferably more or less flexible handle *e*, each wire tooth or bristle *d'* affording one of the assembly of gravers and being yielding, both because of its own flexibility and because of its being yieldably mounted in the material *d''*, as leather of fabric, which is not secured to the handle *e* in such a way as to prevent a certain amount of bulging therefrom—see Fig. 5. The stencil is laid on the surface *A* (shown as a varnish coating on a copper surface *g*) to be treated as shown in Fig. 4, and then the graded incisions are formed therein by striking the surface *A* through the opening in the stencil with the toothed or bristle or graver face of the implement but in such a way that outward of the margin of the opening the stencil will also be struck at the same time the said surface is struck; in other words, so that at the moment of impact the stencil as well as the surface *A* supports the implement. Figure 5 is a fragmentary view showing the positions of the parts at the instant of striking, it being noted that the wire gravers when they encounter the harder copper surface *g* after penetrating the material *A* either "skid" or bend, as shown, either of which effects results in the removal by each graver of a fragment of said material of greater area than is represented by the thickness or gage of the graver. (It will be apparent, too, that the deeper any graver is forced into the surface, i. e., the greater the resistance it encounters, the more material will it displace.) Inward of the margin, as at the region *f*, the resulting incisions will be moreover consequently graded in size, (specifically, in the present example, area) as the result of the convergence here maintained as between the surface *A* and the assembly of gravers by reason of the partial support afforded the latter by the stencil at the moment of impact. By a stencil I do not confine myself to the ordinary device, viz., with an opening therein: It is a matter of some support (however constituted) being present, higher than and adjoining the surface *A*. Nor is this way of carrying out my invention limited to the striking of blows: how the pressure is applied depends on the nature of the surface, the surface *A* in the present example being taken as the usual more or less hard varnish coating on a copper surface *g* which, after it has been formed with the incisions and so exposes thereat the copper will have applied to it the acid or mordant

that acts to etch the exposed copper surface so as to make the latter a printing surface after removal of the coating. In view of what has been said the quality of the gravers to yield is a very important factor in forming the graded incisions when the work is to be done on surface material, as *A*, that is hard or backed by harder material. This quality has a further important advantage in that it makes possible the production of variegated or diversified effects as between areas of a surface treated by different applications of the implement thereto.

If cloud effects of various contours are desired to be printed of coarse stencils with divers irregular forms of openings may be used.

Or I may proceed as follows: Let *h*, Fig. 6, represent a stencil or other support laid on the surface *A*, and *i* a piece of fabric glued to the surface so that close to the support it will be spaced from the surface *A* a distance equal to the thickness of such support, as by bridging the stencil opening *h'*. The fabric will be of suitable coarseness so that the bends *i'* in its threads at one face will make more or less distinct impressions or incisions in a yieldable surface if the fabric is pressed against the latter; for the usual varnish surface *A* this would require the presence of a suitable solvent, as turpentine, to soften the surface, which may be applied to the fabric. If the fabric, with the parts related as in Fig. 6, be now struck or pressed with a tampon *j* (Fig. 7) having convex form, the desired result will follow as before: that is to say, said threads of the fabric here form the gravers (incidentally yielding) and the assembly of gravers so constituted being maintained by the support *h* in a relation of convergence to the surface *A* at the region *h* in Fig. 8 at the moment of impact, i. e., of pressure, incisions graded in size will be formed in said surface.

Describing, now, a way which falls within the second class, i. e., where in the performance of my method the acting face of the assembly of gravers and the surface to be treated do not conform:

A tampon or pad *l* (Fig. 9) is formed either of a wad of indiscriminately massed fabric or of a wad of any other suitable preferably yielding material covered with fabric. Being spheroido-convex, whereas the surface *A* (Fig. 10) is not so but cylindrical or flat in the example illustrated, it does not conform to said surface, so that if laid against it there would be convergence between the latter and the surface of the tampon. The fabric, as before, will be of suitable coarseness so that its threads will make more or less distinct impressions or incisions in a

yielding surface if the tampon is pressed against said surface; if the surface is the usual varnish surface it may be rendered soft by applying a solvent, as turpentine, to the 5 tampon. Upon now applying the tampon, by a blow or pressing, against the surface A the threads of the fabric, which form the assembly of gravers (incidentally yielding), will form impressions or incisions therein,

10 and since the assembly is maintained in a relation of convergence to said surface, due to its normal or convex form, these incisions will be graded at the margin m of the area of contact of the tampon with said surface:

15 See Fig. 11, which also shows not only the margin of said area with the graded incisions but regions n of graded incisions due to forming the tampon with a plurality of the convexities, as shown in Fig. 9.

20 Having thus fully described my invention, what I claim as new and desire to secure by Letters Patent:—

1. In the art of printing, the method of producing the herein-described graded incisions in the surface to be treated which 25 consists in forcing into said surface the acting faces of an assembly of gravers while maintaining said assembly in convergent relation to said surface.

30 2. In the art of printing, the method of producing the herein-described graded incisions in the surface to be treated which consists in forcing into said surface the acting faces of an assembly of yielding gravers 35 while maintaining said assembly in convergent relation to said surface.

3. In the art of printing, the method

of producing the herein-described graded incisions in the surface to be treated which consists in forcing the acting faces of an 40 assembly of gravers connected as a unit against and into said surface as to one region of said assembly while supporting the assembly as to another region thereof at an elevation higher than said surface. 45

4. In the art of printing, the method of producing the herein-described graded incisions in the surface to be treated which consists in forcing the acting faces of an assembly of yielding gravers connected as a 50 unit against and into said surface as to one region of said assembly while supporting the assembly as to another region thereof at an elevation higher than said surface.

5. In the art of printing, the method of producing the herein-described graded incisions in the surface to be treated which consists in forcing the acting faces of an assembly of gravers connected as a 55 unit against and into said surface and at the same time against a support adjoining and arranged at an elevation higher than said surface.

6. In the art of printing, the method of producing the herein-described graded incisions in the surface to be treated which 65 consists in forcing the acting faces of an assembly of yielding gravers connected as a unit against and into said surface and at the same time against a support adjoining 70 and arranged at an elevation higher than said surface.

In testimony whereof I affix my signature.
PERCIVAL J. WOOD.
